[57] CLAIM

The ornamental design for an chemical concentrate dispenser, as shown and described.

DESCRIPTION

FIG. 1 is a perspective view of the top, left side and front side of the ornamental design for a chemical concentrate dispenser showing the invention as it appears in use, on an enlarged scale;

FIG. 2 is a front elevational view of the chemical concentrate dispenser of FIG. 1;

FIG. 3 is a right side elevational view of the chemical concentrate dispenser of FIG. 1, the left side elevational view is a mirror image;

FIG. 4 is a top plan view of the chemical concentrate dispenser of FIG. 1;

FIG. 5 is a bottom plan view of the chemical concentrate dispenser of FIG. 1.

FIGS. 3-5 also show the views of the chemical concentrate dispenser at it would appear in use, mounted on a wall shown in phantom.

The broken line drawing of a wall in FIGS. 3-5 is for illustrative purposes only, and forms no part of the claimed design. No rear view is enclosed since the rear view is plain and unornamental.
